CONTROL DEVICE

Heber L. Newell, Stratford, Conn., assignor to
 General Electric Company, a corporation of
 New York

Application February 8, 1940, Serial No. 317,850

8 Claims. (Cl. 200—138)

My invention relates to a control device and more particularly to a control device for controlling the circuit of an electrical appliance in accordance with temperature changes of the appliance.

Among the desirable prerequisites for a temperature control device of this character is that it be uniform and reliable in operation over its entire controlling range; that it be relatively inexpensive to manufacture yet rugged in construction; that it have a high current rating so that it can readily carry the current of the electrical circuit which it is adapted to control; that it be in the form of a unitary assembly which can be separately rated and calibrated and then readily applied to any particular appliance; that it be provided with simple means for adjusting the calibration of the device within given temperature limits after assembly; and that it be provided with means for preselecting within the given range the temperature to be maintained.

It is the primary object of my invention to provide a new and improved control device having the above mentioned prerequisites.

It has been found that one of the principal factors which causes a non-uniform and unreliable operation of a temperature responsive control device over its operating range is the presence of stresses in the temperature responsive element, usually a bimetallic element, other than the stresses resulting from temperature changes. These stresses may be caused either by the manner in which the element is assembled and secured in its operative position or by the twisting and binding of the element when it is moved in response to a temperature change.

It is a specific object of this invention to provide improved supporting means for the temperature responsive element, the supporting means being constructed and arranged to support the element loosely in its operative position so that substantially no stresses are set up in the blade during assembly thereof and so that binding or twisting of the element during operation of the device will be substantially eliminated.

In accordance with my invention I have provided a control device which is adapted to be constructed and assembled as a unit which can be readily mounted for use in the heating appliance the temperature of which is to be controlled. In one form thereof my improved control device comprises a support in the form of a casing in which is mounted switch means comprising a fixed contact and a movable contact, the latter being mounted on one end of a resilient arm. Loosely supported at its ends within the casing is a bimetallic temperature responsive element which is positioned so that its movement in response to temperature changes will be trans-

mitted to the resilient arm to effect movement of the switch means to a different circuit controlling position. Adjustable stop means is provided to coact with the bimetallic element between its supported ends in order to preselect within given limits the temperature at which the bimetallic element causes the switch means to be operated and additional means are provided for readily varying the calibration of the device so that the maximum and minimum temperature limits of the control may be adjusted after assembly. In order to simplify the construction of my improved control device and to reduce manufacturing costs, the temperature responsive element and the contact arm are constructed and arranged so as to be at the same electrical potential and with such a construction only a relatively simple insulating member is required to insulate the adjusting means from the contact arm and temperature responsive element assembly.

Additional objects and advantages of my invention will become apparent as the following description proceeds and the features of novelty which characterize my invention will be set forth in the claims appended to and forming a part of this specification.

For a more complete understanding of my invention, reference should be had to the accompanying drawing in which Fig. 1 is a sectional elevation of my improved temperature responsive control device; Fig. 2 is a plan view partly in section of the arrangement shown in Fig. 1; Fig. 3 is a view similar to Fig. 1 showing the elements of the control device in a different operative position; and Fig. 4 is a view taken on the line 4—4 of Fig. 1 and looking in the direction of the arrows.

In the drawing I have shown a form of my improved control device which is particularly suitable for use as a temperature responsive control device for an electric roaster. It is to be understood, however, that my invention is not limited to a control device for such an application since the device is suitable and particularly adaptable for use in other types of heating devices such, for example, as electric irons, water heaters, waffle irons, and other such appliances.

Referring to the drawing, it will be noted that my improved control device comprises a substantially rectangular-shaped frame or casing 10 which in the preferred form of my invention is pressed from a single sheet of metal so as to have side walls 11 and a top wall 12. Provided within the frame and lying against the underside of the top wall 12 is a sheet of suitable insulating material 13, such as mica. Secured in the casing 10 at one end thereof is a fixed contact structure which comprises a contact button 14 made of some suitable precious material such as silver and welded or otherwise secured to the

head 15 of a rivet 16 which extends through an opening 16a provided in the casing and is peened over at 17. The rivet 16, in addition to supporting the contact button, serves to secure to the casing 10 the terminal plate 18 upon which is mounted a terminal screw 18a. A suitable insulating washer 19 is provided between the top wall 12 of the casing and the base portion of the terminal plate 18. Mounted in the end of the casing opposite that to which the fixed contact structure is secured is a bracket 20 having a pair of horizontally extending flange portions 21 and 22 connected by a substantially vertical portion 23. The bracket is secured to the casing 10 by means of a rivet 24 which passes through openings provided in the flange portion 21 of the bracket and in the casing and is peened over at 25. Like the rivet 16, the rivet 24 is also arranged so as to secure to the casing 10 a second terminal plate 26 having a terminal screw 26a thereon and a sheet of insulating material 27 is provided between the terminal plate and the top wall 12 of the casing. As shown in Fig. 1, each of the openings provided in the casing for receiving the rivets 16 and 24 has a diameter considerably larger than the rivets in order to prevent grounding of the rivets on the casing and the openings provided in the mica strips 13, 19 and 27 are arranged so as to center the rivets with respect to the enlarged openings in the case.

Arranged to cooperate with the fixed contact button 14 to form a switch means for performing circuit controlling functions is a relatively movable contact button 28 made of a material similar to the contact button 14. The movable contact button 28 is firmly secured to the end of a resilient contact arm 29 which in turn is secured at its opposite end by means of a pair of rivets 30 to the flange portion 22 of the bracket 20. The contact arm 29 is made from a suitable thin resilient material which has been heat treated so as to have the proper resilient characteristics and then cut to the length required for use in the control device. The contact pressure between the fixed and movable contact buttons 14 and 28 is controlled by the resilience and positioning of the contact arm 29. If it is desired to alter the amount of the contact pressure, it is merely necessary to bend the flange 22 of the bracket 20 upwardly or downwardly a slight amount during the assembly operation depending upon whether it is desired to increase or decrease the contact pressure.

From the description thus far, it is apparent that, when the contact arm is moved downwardly, the contact button 28 is moved away from the fixed contact button 14 thereby causing the control device to be moved to the open circuit position, and conversely, when the contact arm 29 is moved upwardly, the control device is in the closed circuit position. It is to be observed that the current controlled by the control device passes from the terminal member 18 through the rivet 16, the fixed contact button 14, the movable contact button 28 and into and through the contact arm 29 to the bracket 20 and thence to the second terminal member 26 through the rivet 24. In order to increase the current carrying capacity of the control device, a thin sheet of low resistance material 31, such as aluminum, is secured to the upper side of the contact arm 29 so as to lie under and in good electrical connection with the contact button 28 and also so as to lie between the contact arm and the flange 22

of the bracket 20. By means of this low resistance path, the current will be shunted around the contact arm so that in operation very little current will be carried by the arm thereby insuring that its elastic properties will be substantially unaffected by local heating currents during the operation of the control device.

As previously pointed out, the control device of my invention is adapted to be actuated in accordance with temperature changes so that the heating circuit or circuit for controlling the heating circuit of an electrical appliance may be controlled thereby in accordance with changes in temperature of the appliance. In order to effect this operation of the control device, I have provided in accordance with my invention a temperature responsive member 32 which in the preferred form of my invention is a bimetallic element comprising two strips of metal having dissimilar temperature coefficients of expansion, such as brass and steel, these two strips being securely welded or brazed together over their entire length and width.

In order to insure uniformity of action of the bimetallic member 32, I have in accordance with my invention provided a novel arrangement for supporting the element 32 in its operative position so that a simple straight section of bimetal can be employed without requiring any preforming or stamping and, in addition, I have provided a supporting arrangement which requires no welding or riveting of the bimetal which usually causes internal stresses to be set up within the bimetal blade which affect its operation. As shown in Figs. 1 and 4, the bimetallic element 32 is adapted to lie between the contact arm 29 and the top wall of the casing 10 and is arranged to extend in substantially the same direction as the contact arm 29 and in substantially parallel relation therewith. As shown, the bimetallic element is loosely supported at each end. The supporting means for one end comprises a slot 33 which is provided in the vertical wall 23 of the bracket 20. The support for the opposite end of the bimetallic element 32 comprises a metallic stud 34 which is riveted to the contact arm 29 near the contact carrying end thereof and is provided with a shank 36 which is adapted to extend through an opening 37 provided in the end of the bimetallic element 32. The diameter of the opening 37 in the bimetal element is made substantially larger than the diameter of the shank 36 so that a loose connection will be formed between the bimetal element and the stud 34. A head 38 is provided at the end of the shank 36 so as to prevent the bimetal blade from being accidentally removed from the stud.

It will be observed that by means of this mounting arrangement, the bimetallic element 32 is loosely mounted in position so that at normal temperatures there are no stresses set up in the element. Of course, the combination of the slot supporting means at one end and the pin and opening supporting means at the opposite end provides some lateral restrain on the bimetal element, particularly when the entire assembly is moved or shaken. However, this restraint merely serves to constrain the elements so that it will be maintained in its operative position in the control device. For all practical purposes and in so far as the thermal characteristics of the bimetal element are concerned, it may be said that the bimetal element floats in the control device. This floating feature is, as previously explained, very important in that it insures

uniformity and reliability of operation of the bimetal element over the range of adjustments thereof and eliminates initial stresses in the blade and also stresses arising from bending or twisting of the blade during operation of the control device.

The bimetallic element is mounted in the control device so that the metal having the higher coefficient of expansion is on top as viewed in Fig. 1. Thus upon an increase in temperature, the bimetal will tend to bow upwardly in the center which bowing produces a downward deflection of the ends. This latter motion will be transmitted through the stud 34 to the contact arm 29 causing an opening of the contacts at some predetermined temperature. It is to be observed that both the bimetal element and the contact carrying arm 29 are at substantially the same potential. This factor simplifies the problem of insulation within the casing 10 and also the problem of insulation of the temperature adjusting means to be described below with respect to the bimetal element and the contact arm.

In order to control the temperature at which the control device operates, I have provided an adjusting screw 39 having a rounded end 40 which is adapted to engage a suitable ceramic insulating bushing 41 which is supported in an opening provided in the bimetallic element 32 intermediate its ends. The bushing 41 is molded from some suitable ceramic material and serves not only as the surface against which the end of the adjusting screw 39 abuts but it also serves to insulate electrically the bimetal element and the adjusting screw. The adjusting screw is threadedly supported in a threaded bushing 42 which in turn is threadedly supported in a threaded collar 43 secured to the top wall of the casing 10. The bushing 42 is provided at the upper end with a knurled portion 44 onto which is pressed an operating shaft 45 which is provided with a slot 46 extending along its length. The threads on the collar 43 and the bushing 42 are arranged so that rotation of the shaft 45 counterclockwise as viewed in Fig. 1 causes the rounded end of the adjusting screw to move downwardly with respect to the bimetal blade whereas movement of the shaft 45 clockwise causes the rounded end of the adjusting screw to be moved upwardly into the collar.

In order to limit the rotation of the shaft 45 and thereby limit the movement of the rounded end of the adjusting screw with reference to the insulating bushing 41, there is provided on the shaft 45 adjacent the lower end thereof a disk 47 having an inwardly extending tab 48 which is adapted to engage the longitudinal slot 46 provided in the shaft so that rotation of the disk with reference to the shaft will be prevented. Directly opposite the inwardly extending abutment 48 is an outwardly extending abutment 49. This abutment is adapted to engage a tongue 50 pressed out of a bracket 51 which is welded or otherwise suitably secured to one of the longitudinal side walls of the casing 10. The tongue 50 in cooperation with the abutment 49 provided on the disk 47 function as stops to limit the rotation of shaft 45 so that the total rotation thereof is less than 360 degrees. In order to provide frictional restraint on the shaft 45 so that it is maintained in any of its adjusted positions, a hairpin spring 52 is provided which extends around one portion of the shaft 45 and is constrained at its ends by means of a pair of tabs 53 which are pressed out of the top wall 54 provided on the bracket 51. The bracket 51 not only

serves to support the hairpin spring and provide the stop 50 but, in addition, it serves as the means for mounting the control device in an appliance, such as an electric roaster, and a pair of openings 55 is provided in the wall 54 of the bracket for receiving screws for securing the control device to the side wall of an appliance such as an electric roaster.

In order to enclose the operative elements of the control device, a cover 56 is secured to the casing 10 by means of rivets 57. The cover 56 is made from some good conducting material, such as aluminum, and is provided with a vertically extending flange portion or duck bill 58 which is adapted to lie adjacent the surface of the appliance the temperature of which is to be controlled so as to conduct heat readily to the control device. In a roaster, for example, the duck bill 58 is adapted to lie between the bottom surface of the roaster and the bottom heating units therefor. It is to be understood, of course, that any other suitable cover might be employed for the control device.

As previously described, the adjusting screw 39 is threadedly mounted within the bushing 42 and, by adjusting this screw with reference to the bushing, the temperature limits of the control device may be adjusted. In accordance with one phase of my invention, the temperature limits or the temperature range through which the control device operates vary from a manually settable off position at room temperature to a predetermined high temperature setting. Thus, in calibrating the device, the adjusting screw is set so that when the shaft 45 has been rotated counterclockwise, as viewed in Fig. 1, until the abutment 49 engages the stop 50, the rounded end 40 of the adjusting screw will have engaged the insulating button 41 and caused the bimetal element and contact arm assembly to be moved downwardly to cause the movable contact 28 to move out of engagement with the fixed contact 14. The adjusting screw 39 is positioned so that this manual opening of the control device takes place during approximately the last 20 degrees of movement of the shaft 45 in the counterclockwise direction. With the adjusting screw thus positioned, the high temperature limit of the control device is also determined for in rotating the shaft in a clockwise direction until the abutment 49 again engages the stop 50, the end 40 of the adjusting screw will have been moved away from the insulating button 41 a predetermined amount.

While this adjustment is the preferred adjustment for my improved control device, it will be understood that by means of the fine adjustment obtainable with the screw 39 and the rough adjustment obtainable by means of the threaded relation between the sleeve 42 and the bushing 43 when the collar 43 is raised on the shaft 45 so that the abutment 49 does not engage the stop 50, any other temperature limits may be selected for the control device.

It is to be observed that by means of a separate mounting of the adjusting screw 39, the position of the adjusting screw may be varied a small amount after the device has been assembled and is checked for calibration so that the device will function at the desired high temperature limit. This adjustment, of course, does not destroy the adjustment for an off position at normal or room temperatures but merely causes this off position to be obtained either earlier or later than that previously set depending upon whether the adjusting screw is moved inwardly

or outwardly to thereby engage the insulating button 41 sooner or later when the shaft 45 is rotated in a counterclockwise direction into engagement with the stop 50.

In considering the operation of my improved control device, reference will be had to Figs. 1 and 3. Fig. 1 shows the operative position of the component elements of the control device when the shaft 45 has been rotated in the counterclockwise direction until the abutment 49 engages the stop 50. In this position, the contacts are open as shown. Fig. 3 represents the position of the component elements when the shaft 45 has been rotated the full distance in the clockwise direction so that the abutment 49 engages the stop 50. This represents the maximum temperature setting for the control device. Assuming that the control device is set to maintain the maximum temperature for which it is calibrated, that is, assuming that the elements are in the position shown in Fig. 3, the electrical circuit controlled by the device will be energized and the temperature of the appliance heated by this electrical circuit will begin to rise. Heat will be conducted through the duck bill 58 to the control device and the bimetal element will start to bow upwardly. As long as the temperature of the device being controlled is below the predetermined maximum temperature, the bowing of the bimetallic element will be unimpeded and, because of the floating arrangement by which it is supported, no binding of the element will occur during this bowing operation. When the device being controlled approaches the temperature at which the control device is set to operate, the bimetallic element will have bowed sufficiently far so as to cause the insulating button 41 to move up into engagement with the rounded end 40 of the adjusting screw which acts as a stop. The adjusting screw thereafter impedes further bowing of the temperature responsive element in response to increase in temperature and an additional temperature rise causes the right-hand end of the bimetal element (as viewed in Fig. 1) to deflect downwardly about the point of contact between the insulating button 41 and the end of the adjusting screw 40 as a pivot point. This downward deflection of the right-hand end of the bimetal is transmitted through the stud 34 to the contact arm 29.

As previously described, the contact arm is made from resilient material and is inclined upwardly so that a predetermined amount of contact pressure will exist between the fixed and movable contacts. The initial downward deflection of the right-hand end of the temperature responsive element is resisted or opposed by the upward component of force exerted by the resilient contact arm. However, when the temperature of the device being controlled attains the predetermined maximum temperature for which the control device is set to operate, the downward component of force exerted by the end of the bimetal element on the contact arm is sufficient to overcome the contact pressure between the fixed and movable contacts and thereby to cause the control device to operate so as to deenergize the heating circuit of the appliance being controlled.

With the heating circuit deenergized, the temperature of the appliance being controlled will decrease and this decrease in temperature causes a straightening out of the bimetal element which is manifested first by an upward deflection of the right-hand end of the element. When the

temperature is decreased to the point that the right-hand end has deflected upwardly so that its downward component is less than the upward component of the contact arm, then the contacts will close and the heating circuit will be again energized so as to raise the temperature of the appliance. When the predetermined desired temperature is again reached, the control device will function as previously described.

10 It is to be observed that during this entire operation the bimetallic element is relatively free to move with reference to its supporting means and therefore binding or twisting, which would materially affect the uniformity of operation of the control device, is eliminated. Of course, it will be understood that any temperature setting between the off position at room temperature and the maximum temperature may be selected by suitably positioning the shaft 45 and that the control device will function in the manner described for any of these intermediate settings.

When it is desired to deenergize the appliance completely, that is, to assume manual control thereof, it is necessary only to rotate the shaft 25 45 in the counterclockwise direction, as viewed in Fig. 2, until the abutment 49 engages the stop 50. Under these circumstances the rounded end 40 of the adjusting screw will be moved down 30 against the insulating button 41 and will have caused the contact arm to be moved downwardly so that the contact 28 is moved away from the contact 14, as previously described. With the adjusting screw thus in engagement with the insulating button 41, the control device cannot 35 reclose at any normal temperature, such as room temperature, but it is positively held in the open circuit position.

While I have shown a particular embodiment of my invention, it is to be understood, of course, that I do not wish to be limited thereto since many modifications may be made, and I, therefore, contemplate by the appended claims to cover all such modifications as fall within the true spirit and scope of my invention.

45 What I claim as new and desire to secure by Letters Patent of the United States, is:

1. A control device for controlling an electrical circuit in accordance with temperature changes comprising a support, switch means 50 mounted on said support, a bracket having a slot 55 therein mounted on said support at a point remote from said switch means, a resilient arm having one end secured to said bracket and its opposite end free to move to actuate said switch means, a stud mounted on said arm near said free end and a bimetallic temperature responsive element having one end loosely supported by said stud and its opposite end extending through said slot in said bracket so as to be 60 loosely supported by said bracket, said bimetallic element being constructed and arranged to cause said arm to move said switch means in accordance with temperature changes.

2. In a control device for controlling an electric circuit in accordance with temperature changes, a casing having a top wall, a stationary contact secured to said top wall, a bracket having a slot therein secured to said top wall at a point remote from said stationary contact, a resilient arm fixed at one end to said bracket and having its opposite end free to move, a movable contact mounted on said free end of said arm and adapted to engage said fixed contact, a stud mounted on said arm intermediate its ends, and a temperature responsive element

having one end loosely supported by said stud and its opposite end extending through said slot in said bracket so as to be loosely supported by said bracket, said bimetallic element being constructed and arranged to cause said arm to be moved in accordance with temperature changes.

3. In a control device for controlling an electric circuit in accordance with temperature changes, a support, switch means including a relatively fixed contact mounted on said support and a relatively movable contact, a bracket having a slot therein secured to said support at a point remote from said fixed contact, a resilient arm fixed at one end to said bracket and carrying at its opposite end said movable contact, a stud mounted on said arm near said movable contact, a bimetallic element having one end extending through said slot in said bracket so as to be loosely supported by said bracket in spaced relation to the fixed end of said arm and having its opposite end loosely supported on said stud so that movement of said end in response to temperature changes will cause movement of said arm, and means for preventing said bimetallic element from being accidentally moved off said stud.

4. A control device for controlling an electrical circuit in accordance with temperature changes comprising a support, a bracket having a slot therein mounted on said support, a resilient arm mounted on said bracket, switch means associated with said support on said arm and adapted to be actuated in accordance with movement of said arm, a bimetallic element having an opening in one end and having its opposite end extending through said slot in said bracket so as to be loosely supported by said bracket in spaced relation to said arm, means for loosely supporting said end of said bimetal having said opening therein on said arm and for transmitting movement of said end of said bimetal to said arm, said means comprising a stud mounted on said arm and having a portion of reduced diameter adapted to be inserted in said opening in said bimetal element, and a head formed on said portion of reduced diameter to prevent said bimetal element being accidentally removed therefrom after it has been assembled thereon.

5. In a control device for controlling an electrical circuit in accordance with temperature changes, a casing having a top wall, a stationary contact secured to said top wall, a bracket having a slot therein secured to said top wall at a point remote from said stationary contact, a resilient arm fixed at one end to said bracket and having its opposite end free to move, a movable contact on said free end of said arm and adapted to engage said fixed contact, a stud mounted on said arm, and a temperature responsive element lying between said top wall of said casing and said arm in spaced relation to said arm, said element having one end loosely supported by said stud and its opposite end extending through said slot in said bracket so as to be loosely supported by said bracket, and means for causing said end of said bimetal element which is mounted on said stud to deflect downwardly at a predetermined temperature an amount sufficient to cause said arm to move said movable contact away from said fixed contact.

6. A control device for controlling an elec-

trical circuit in accordance with temperature changes comprising a casing, a bracket mounted on said casing and having a slot therein, a resilient arm secured at one end to said bracket and having its opposite end free to move, switch means associated with said casing and said arm and adapted to be moved to different circuit controlling positions in accordance with movement of said arm, a bimetallic element having one end extending through said slot in said bracket so as to be loosely supported thereby and having its opposite end loosely associated with said arm near the free end thereof so as to cause movement of said arm in accordance with temperature changes, an insulating member mounted on said bimetallic element intermediate its ends, an adjusting screw mounted on said casing and having an end adapted to be engaged by said insulating member to control the temperature at which said bimetallic element causes said arm to move said switch means to a different circuit controlling position.

7. In a control device for controlling an electric circuit in accordance with temperature changes, a casing, a bracket mounted in said casing and having a slot therein, a resilient arm mounted on said bracket, contact means associated with said casing and said arm and adapted to be actuated by movement of said arm so as to perform a circuit controlling function, a bimetallic element spaced from said arm and having one end extending into said slot so as to be loosely supported by said bracket, a stud mounted on said arm adjacent the free end thereof and constructed and arranged to engage loosely the opposite end of said bimetal element and to support it in spaced relation with respect to said arm, an insulating member mounted on said bimetallic element intermediate its ends, an adjusting screw having a rounded end adapted to be engaged by said insulating member, and means for varying the position of said end of said adjusting screw relative to said insulating member to regulate the temperature setting of the control device, said last mentioned means being movable between two limiting positions one of which corresponds to a predetermined high temperature and the other of which corresponds to a manually settable "off" position at room temperature.

8. A control device for controlling an electrical circuit in accordance with temperature changes comprising a switch, a movable arm for actuating said switch, a bimetallic element, supports adjacent the ends of said element, said supports being constructed and arranged to loosely engage and support said element to permit an unrestricted bowing action of said element in accordance with temperature changes thereof, one of said supports being fixed and the other movably mounted and operatively connected to said arm, a stop arranged to engage said element between said supports to limit the bowing action of said element beyond an amount corresponding to a predetermined temperature thereof whereby force is then transmitted through the support connected to said arm to cause movement of said arm and actuation of said switch, and means for varying the position of said stop relative to said element to permit adjustment of said predetermined temperature.

HEBER L. NEWELL.
